UNITED STATES PATENT OFFICE

RALPH O. HELGEBY, OF FLINT, MICHIGAN, ASSIGNOR TO A C SPARK PLUG COMPANY,
OF FLINT, MICHIGAN, A COMPANY OF MICHIGAN

AMMETER

Application filed May 28, 1928. Serial No. 281,098.

This invention relates to ammeters, and has particular reference to improvements relating to supporting means for the various parts of the ammeter.

5 The invention has for its object to construct an ammeter which will have a combined conductor and supporting means.

The object of the invention is accomplished by providing a U-shaped conductor or supporting frame having a pair of laterally projecting wings at the legs of the U. The frame or conductor is secured to the ammeter casing by means of bolts passing through the wings.

15 The U-shaped portion of the supporting frame is provided at the base of the U with a slot for the reception of a unit on which is mounted the pointer swinging mechanism. At substantially the ends of the legs of the 20 U a second slot is provided, in which a permanent magnet is mounted.

The outer portion of the base of the U is provided with studs or projections the purpose of which is to fasten the dial to the 25 supporting member.

On the drawing, Figure 1, is a front view of the ammeter of the invention with the dial broken away.

Figure 2, is a section on the line 2—2 of 30 Figure 1.

Figure 3, is a rear view with parts broken away to better illustrate the invention.

Figure 4 is a section on the line 4—4 of Figure 1.

35 Referring to the drawing, the numeral 10, indicates the casing of the ammeter. At the outer rear portion of the casing there is applied an insulating strip 12, while a second insulating strip is applied at the inside over the 40 bottom 16, of the casing 10. Seated on the insulating strip 14, are the wings 18, and 20, of a supporting frame or conductor indicated as a whole at 22. Bolts 24 and 26, pass through openings in the wings 18 and 20, the insulating strips 12 and 14, and the bottom 16 of the casing and are held in position by means of the lock nuts 28 and 30.

The conductor or supporting frame 22, is shown as of generally U-shape, the U-shaped 45 portion comprising the base 32 and the legs

34 and 36. At the inner portion of the base 32 there are provided the grooves or slots 38 extending at both sides of the legs 34 and 36 and in which slots there is supported the plate 40 of a unit 42 which may be termed 55 the pointer swinging mechanism unit. This unit comprises the integral arm 44, bent into U-shape and having its lower portion 46 extending underneath and forming with the plate 40 a mounting means for the shaft 48 60 on which there is mounted the armature 50 and the pointer 52.

Positioned substantially at the ends of the legs 34 and 36 of the U portion 22, is a second pair of co-operating grooves or slots 54 65 in which there is inserted the permanent magnet 56.

The plate portion 40 as well as the magnet 56 may be rigidly secured in their respective slots 38 and 54 either by a press 70 fit, or by pinching the metal together at the grooves.

The casing is provided with the usual transparent or glass front 58, and the bezel ring 60 is secured over a flange 62 on the 75 casing and over the glass to rigidly hold the transparent front to the casing.

The base 32, of the U-shaped supporting member 22 is provided with the integral lugs or projections 64 and 66 which serve 80 as a means for holding the dial rigidly on to the base of the supporting frame 22. The dial is secured by riveting over the ends of the lugs 64 and 66.

By the structure of the invention as described it will be apparent that there has been provided a compact and secure arrangement for holding the various parts of the ammeter in secure relations and that the conductor also serves as a supporting 90 member.

I claim:

1. In an ammeter, a conductor having a plurality of slots, a pointer swinging mechanism mounted in one slot and actuated in 95 response to the energization of said conductor, and a permanent magnet mounted in another slot and adapted to bias said mechanism to its zero position.
2. In an ammeter, a U-shaped conductor 100

having a slot at the base of the U and a slot at the extremity of each leg of the U, a pointer swinging mechanism supported in one of said slots, and a permanent magnet supported in the other slot.

5 3. In an ammeter, a U-shaped supporting frame for the ammeter mechanism, a magnet mounted at the end of legs of the U, a pointer swinging unit mounted on the U, and a dial mounted at the base of the U by means of lugs integral with the frame.

10 4. In an ammeter, a U-shaped supporting frame, flanged wings on the legs of the U by means of which the frame is secured to the casing, a pointer swinging mechanism mounted on the inner side of the base of the U, a dial mounted by means of integral lugs on the outer side of the base of the U, and a permanent biasing magnet mounted 15 at the end of the legs of the U.

20 5. In an ammeter, a U-shaped conductor having a slot at the base of the U and a slot at the extremity of each leg of the U, a pointer swinging mechanism supported in one of said slots, a permanent magnet supported in the other slot, a dial, and integral lugs on said conductor by means of which said dial is secured to said conductor.

25 6. In an ammeter, a U-shaped supporting frame for mounting the ammeter parts, a pointer swinging mechanism mounted as a unit at the base of the U, and a magnet mounted on said frame at the ends of the legs of the U.

30 7. In an electric measuring instrument, a U-shaped supporting frame, and pointer swinging mechanism separately constructed and mounted at the base of and inclosed within the U, and a magnet mounted at the 35 ends of the legs of the U.

40 8. In an electric measuring instrument, a frame having a plurality of grooves, a pointer swinging mechanism constructed as a unit, said mechanism including a plate, said plate adapted to be received in some of 45 said grooves to rigidly mount the mechanism, and a magnet mounted in other of said grooves.

45 9. In an electric measuring instrument, a 50 U-shaped frame having a plurality of grooves inside the U, a pointer swinging mechanism constructed as a unit, said mechanism including a plate mounted in some of said grooves to rigidly hold the mechanism, and a permanent magnet mounted in other of said grooves.

55 10. In an electric measuring instrument, a U-shaped frame having a plurality of grooves, a pointer swinging mechanism constructed as a unit including a plate, said plate adapted to be received in grooves at the base of the U, and a permanent magnet mounted in grooves at the inner side of the 60 ends of the legs of the U.

65 11. In an electric measuring instrument,

a casing, insulation in said casing, a frame mounted in said casing, said frame having a plurality of oppositely disposed grooves, a pointer swinging mechanism mounted in one pair of said grooves, and a magnet 70 mounted in another pair of said grooves, said magnet spaced from said insulation.

In testimony whereof I affix my signature.

RALPH O. HELGEBY.
